(57) CLAIM

(73) Assignee: Wilson Sporting Goods Co., Chicago, IL (US)

We claim the ornamental design for a central portion of a game racquet with separate head and handle portions, as shown and described.

() Term: 14 Years

DESCRIPTION

(21) Appl. No.: 29/160,013

(22) Filed: May 2, 2002

Related U.S. Application Data

(63) Continuation-in-part of application No. 09/849,965, filed on May 4, 2001.

FIG. 1 is a front view of a central portion of a game racquet with separate head and handle portions of the present invention.

(51) LOC (7) Cl. 21-02
(52) U.S. Cl. D21/729
(58) Field of Search D21/729-733; 473/524, 546

FIG. 2 is an enlarged front view of the central portion shown in FIG. 1.

(56) References Cited

FIG. 3 is a side view of the central portion shown in FIG. 1. FIG. 4 is a bottom view of the central portion shown in FIG. 1 including broken (dashed) lines for the purpose of illustrating environmental elements only environmental.
